ATTORNEYS.

UNITED STATES PATENT OFFICE

RALPH WYCKOFF, OF SAN JOSE, CALIFORNIA

WINDOW CONSTRUCTION

Application filed March 19, 1930. Serial No. 437,031.

This invention relates to a window construction.

It is the primary object of the invention to provide a window construction wherein the sash may be opened or closed by an operating mechanism, which latter is actuated by remote control means, so as to allow the turning of the sash without necessitating the raising of screens or the like usually mounted in the window opening.

Particularly it is the object of the invention to adapt a metal sash for connection to a window opening and closing mechanism, the latter being operable from the interior of the compartment in which the window is disposed; this adaptation being accomplished by the provision of an extension sash bar extending below the bottom sash member to overlap and be connected to the sash operating mechanism.

Other objects and advantages are to provide a window construction that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

The invention is clearly illustrated in the accompanying drawing wherein,

Fig. 1 is a sectional view of the lower part of my window structure, the section being taken on the line 1—1 of Fig. 2.

Fig. 2 is a sectional plane view of the window.

Fig. 3 is a sectional plane view of the operator and its mounting on the jamb.

Fig. 4 is a front view of the window; and

Fig. 5 is a front view of the window, showing the downwardly extended jambs.

The invention is particularly constructed for use in connection with metal, or steel window frames.

It is necessary that such window frames present a substantially smooth finished outer surface, yet be connected to a suitable window opening mechanism. Screens are commonly used on the inside of the window openings, and it is desirable that metal windows be so constructed as to permit the same to be opened or closed at pleasure by an operating mechanism without necessitating the raising of said screens.

In carrying out my invention I make use of a metal window frame 6 mounted in the usual manner in a window opening 7 of a wall 8. The jambs 9 of the frame 6 are extended below the lower, horizontal frame member 11 so as to form the opposite ends of a recess below the said member 11. Adjacent an end of the said recess a pocket 12 is formed below the stool 13 of the window opening to accommodate a suitable operator mechanism 14 therein.

A metal casement sash 16 is hinged at a vertical edge thereof to one of the jambs 9 to open and close around said vertical edge. It is to be noted that each side of the frame 6 is of angle iron or steel of a section resembling the letter L; and each side of the sash 16 is of a cross section of an angle iron with an outwardly extending flange 17 on the outer edge thereof, so as to effect a double seal of the window frame, by reason of the abutment of the inner and outer flanges of the sash members to the respective flanges and edges of the frame members.

In order to allow the connection of the operator 14 to the sash 6, without altering the relation between the frame 6 and the sash 16, an extension sash bar 18 is formed on the outer flange 17 of the lower horizontal sash member 19 of the sash 16. The extension sash bar 18 is integral with the flange 17, and extends downwardly in continuation thereof. The bar 18 overlaps the recess below the frame member 11 so as to cover the same. It is to be noted that the said recess extends down to the top of the sill 21, and therefore the bar 18 also extends to the top of the sill.

The mechanism 14 is connected to the extension bar 18 by means of a lever arm 22.

slidable in a vertical yoke 23, which latter is fixed on the inner face of the bar 18.

There are various types of operators in use at present and either one of them may be used in connection with the above described metal window construction. In the present illustration the arm 22 is pivoted in a stationary box 24, and has at its pivoted end a peripherally notched disc 26 to engage with a worm 27, on a rod 28 journaled in the box 24 at right angles to the arm 22. The box 24 may be either secured into the pocket 12 directly, or it may be secured by means of screws 29 to the downwardly extended portion of the hinge-carrying jamb 9. In the latter instance a true adjustment is more readily achieved, and the frame and the sash and the operator may be sold as an assembled, adjusted unit. The free end of the rod 28 extends beyond the wall of the box 24 and is provided with a socket of annular cross section therein, into which fits the end of a crank 31 extending thru the wall or thru the stool 13 of the window opening into the interior of the compartment or room.

The sash 16 can be opened or closed by the rotation of the crank 31, which in turn actuates the operator 14 to swing the arm 22 outwardly or inwardly. The arm 22 exerts a pressure on the extension sash bar 18 to turn the sash 16 around its hinges in the desired direction. Thus the window may be opened or closed without necessitating the removal of the screen usually disposed above the stool 13. It is to be noted that the sash completely seals the frame and the operator does not interfere with the usual construction of metal window fitting. The operator and the co-acting operating elements of the metal window sash and metal frame are disposed entirely below the lower horizontal frame member 11. The appearance of such metal windows is attractive, the operator is usually concealed in the recess, and the unused part of the recess below the window frame may be filled solid.

It will be recognized that a particularly simple construction is provided, whereby the use of operators in connection with metal windows is greatly facilitated. Metal windows of this construction may be sold as a unit and be mounted in the window openings in the usual manner.

It is to be also noted that when the window is constructed in accordance with my invention, the stool is left entirely free from and unobstructed by the fasts and adjusting arms; the sight line of the glass is left free and unobstructed by mechanical adjusters. The operator is disposed entirely below the frame. The frame and sash constructed as heretofore described, render the window water tight and air tight, when closed. The window is readily closed or opened and when the window is properly closed, it is also se-

curely locked, thereby eliminating all fastenings and catches of every variety now in common use in connection with the ordinary steel sash casement windows.

Having thus described this invention, what I claim and desire to secure by Letters Patent is:

1. Operating means for a casement sash comprising a fixed sill member having a recess formed below an outside portion thereof, an extension on the sash extended to below the level of the sill member and over said recess to cover the latter, an operating element on the inside face of the said extension facing said recess, means in the recess to swingably support said element, and actuating means extended under the sill member and through the wall and connected to said element to turn the said element to open and close the window.

2. The combination with a metallic casement frame of substantially Z shaped cross section, an outwardly opening window having a metallic sash of similar cross section; of operating means for opening and closing the sash comprising a receptacle formed below the underside of the frame, an extension on the sash extended downwardly to cover said receptacle on the outside, an operating element on the inside face of said extension, means in said receptacle to swingably support said element, means connected to said element to swing the same into and out of said receptacle thereby to swing the sash respectively into open and closed positions, and control means whereby said swinging means is actuated at will.

3. Operating means for a casement sash comprising a sill member secured in a wall, said member having a recess formed at its underside in said wall, an extension on the sash extended over the said recess to cover the same, an operating bar alongside the face of said extension adjacent said recess, means to slidably connect said bar to the said extension, means to pivotally support an actuating mechanism in the recess adapted to turn said bar around its pivot, thereby to open and close the said sash, and control means extended through the wall, whereby said actuating means is manipulated.

In testimony whereof, I have hereunto set my hand at San Jose, California, this 20th day of February 1930.

RALPH WYCKOFF.
